(57) CLAIM

The ornamental design for a runner's straw, as shown and described.

DESCRIPTION

FIG. 1 is a rear perspective view of a runner's straw showing my new design, wherein a partial view of a hand is shown in broken lines for illustrative purposes only and forming a part of the claimed design;

FIG. 2 is a front perspective view of a runner's straw showing my new design, wherein a partial view of a hand is shown in broken lines for illustrative purposes only and forming a part of the claimed design;

FIG. 3 is a top view thereof;

FIG. 4 is a left side view thereof;

FIG. 5 is a bottom view thereof;

FIG. 6 is a rear view thereof;

FIG. 7 is a right side view thereof; and,

FIG. 8 is a front view thereof.
